CLAIM

The ornamental design for an electrical connector, as shown
and described.

DESCRIPTION

FIG. 1 is a front perspective view of the first embodiment of
an electrical connector showing our new design;
FIG. 2 is a rear perspective view thereof;
FIG. 3 is a front view thereof;
FIG. 4 is a cross-sectional view taken along the line 4-4 as
seen in FIG. 3;

FIG. 5 is a rear view of the first embodiment;
FIG. 6 is a left-side view thereof;
FIG. 7 is a right side view thereof;
FIG. 8 is a top view thereof;
FIG. 9 is a bottom view thereof;

FIG. 10 is a front perspective view of the second embodiment
of an electrical connector showing our new design;
FIG. 11 is a rear perspective view thereof;
FIG. 12 is a front view thereof;
FIG. 13 is a cross-sectional view taken along the line 13-13
in FIG. 12;

FIG. 14 is a rear view of the first embodiment;
FIG. 15 is a left-side view thereof;
FIG. 16 is a right side view thereof;
FIG. 17 is a top view thereof; and,
FIG. 18 is a bottom view thereof.

The broken lines in the drawings illustrate portions of the
electrical connector that form no part of the claimed design.

1 Claim, 14 Drawing Sheets
